Term of patent 14 years

To all whom it may concern:

Be it known that I, George H. Packwood, Jr., a citizen of the United States residing in Clayton, St. Louis County, State of Missouri, have invented a new, original, and ornamental Design for a Soap Dispenser or the like, of which the following is a specification, reference being had to the accompanying drawing forming part thereof, in which

Fig. 1 is a top plan view of a soap dispenser showing my new design;

Fig. 2 is a front elevational view thereof; and,
Fig. 3 is a side elevational view.

The characteristic features of my design reside in the transparent windows which contrast with the opaque body of the dispenser and the depending operating lever.

I claim:

The ornamental design for a soap dispenser or the like, substantially as shown and described.
